UNITED STATES PATENT OFFICE.

WILLIAM N. SIMPKINS, OF STREATOR, ILLINOIS.

GATE.

SPECIFICATION forming part of Letters Patent No. 657,462, dated September 4, 1900.

Application filed March 22, 1900. Serial No. 9,717. (No model.)

To all whom it may concern:

Be it known that I, WILLIAM N. SIMPKINS, a citizen of the United States, residing at Streator, in the county of La Salle and State 5 of Illinois, have invented a new and useful Gate, of which the following is a specification.

This invention relates to improvements in gates, and the particular object is to provide 10 means whereby a swinging gate may be easily raised to pass over an obstruction, as when the ground slopes or in case of snow, or to allow small stock, as sheep or pigs, to pass thereunder.

15 A further object is to provide, in connection with the above mechanism, simple means for securely locking the gate in closed position, so that there is no chance of its becoming accidentally opened.

20 To set forth the invention fully, the preferred form of the same is described in the following specification, and shown in the accompanying drawings, forming part of the same, and in which—

25 Figure 1 is an elevation of a swinging gate, showing my invention applied thereto. Fig. 2 is an enlarged view of the lower portion, clearly showing the construction and arrangement of the lower hinge. Fig. 3 is a horizontal longitudinal section on the line $\alpha\alpha$ of Fig. 2. Fig. 4 is a view of the crank-arm detached. Fig. 5 is a view of a slightly-modified manner 30 of mounting the slideable hinge member.

Similar numerals of reference designate 35 like and corresponding parts in the several figures of the drawings.

In the drawings the numeral 10 designates a gate of ordinary construction, 11 and 12 designating the hinge and locking posts, respectively, and 13 the upper hinge for the same, which may be of any construction desired.

40 The lower hinge 14 preferably comprises a curved slide-bar 15, slidably mounted upon the lower corner of the gate and provided in its end with the hinge-eye 16, which receives the hinge pin or pintle 17, fastened to the post 11. In mounting the slide-bar 15 upon the gate a plate 18 is provided, which is fastened 45 in any desirable manner to the lower rail of the gate, preferably by bolts 19. This plate is provided at one end with the vertically-

arranged guide-strap 20 and near the opposite end, at its side edges, with the vertically-lined perforated ears 21. The slide-bar 15 is arranged between the ears 21 and under the guide-strap 20, whereby it has a sliding movement upon the plate 18. Passing through the perforations in the ears 21, and thereby forming a retainer for the bar 15 is the spring 55 22. This spring is bowed at its central portion, the free end being bent downwardly and engaging behind the pin 23, carried by the bar 15. The end of the bar 15, opposite the pivot-eye 16, is provided with the angular brace 24, which is detachably secured to the end of the bar by a bolt 25 and which forms at the end of the bar 15 a space for the reception of the crank-arm 26. The crank-arm 26 is rigidly attached to the lower end 60 of the long lever 27, which in its normal position extends diagonally across the gate and is pivoted thereto at its lower end by means of the angular brace 28 and bolt 29. The crank-arm 26 preferably consists of the arm 70 75 30 and brace 31, the ends of which are provided with a plurality of openings, whereby the crank-arm may be adjusted upon the lever 27. The end of the crank-arm fits between the adjacent faces of the brace 24 and 80 the bar 15, and a pivot-bolt 32 passes through openings in the end portions of these several members, thereby pivotally connecting the crank and the slide-bar. At the free end of the gate is the guide-rod 33, which prevents 85 the lateral displacement of the free end of the lever.

To lock the gate in closed position, there is provided at the lower end of the locking-post the angular projecting keeper 34, having its 90 end upturned, forming a seat for the lower end of the gate. The upper portion of the locking-post is provided with a similar projecting keeper 35, having its end turned downwardly, forming a seat or stop for the free end 95 of the lever 27. Assuming the gate closed, the gate is so balanced that its weight is slightly greater than the counteracting weight of the lever 27 and the pressure of the spring 22. In this position the free end of the gate will 100 rest upon the keeper 34, thus relieving all strain upon the hinge-post 11 and the gate 10. The free end of the lever 27 will also be engaged under the keeper 35. To operate

the gate, a downward pressure upon the free end of the lever will disengage it from the keeper 35 and at the same time the free end of the gate will be raised and disengaged from the keeper 34, whereupon the gate may be swung open. The height to which the gate may be raised is only limited by the guide-rod 33, and this may be readily changed by adjusting the crank-arm 26.

- 10 In the modification shown in Fig. 5 the spring 22 is not used, but instead a pair of guide-straps 20^a are provided, through which the sliding bar 15 passes. In this construction the lever 27 is made heavy enough to 15 nearly counterbalance the weight of the gate, or a weight may be placed upon the lever, if desired.

From this description it will be seen that a very simple construction is provided that 20 admits of the raising of the gate to allow small animals to pass thereunder or that will permit the use of a swinging gate upon sloping ground or in snow, above which it may be raised. Another advantage lies in the 25 fact that when the gate is in its closed position all strain is taken therefrom and from the hinges, whereby there is no liability of its sagging. Moreover, the construction affords a reliable locking device, which fastens

- 30 the gate at both its upper and lower ends, and the lever extending diagonally across the gate forms a strengthening-bar for the same.

The bar 15 has been described and claimed as the "slidable hinge member" in order to 35 clearly designate the same and distinguish it from the other hinge members and emphasize the relative sliding movement between it and the gate.

From the foregoing it is thought that the 40 construction, operation, and many advantages of the herein-described invention will be apparent to those skilled in the art without further description, and it will be understood that various changes in the size, shape, 45 proportion, and minor details of construction may be resorted to without departing from the spirit or sacrificing any of the advantages of the invention.

Having thus described my invention, what 50 I claim as new, and desire to secure by Letters Patent, is—

1. The combination with a swinging gate, of a hinge, one member of which has a sliding engagement with the gate, a lever pivoted 55 upon the gate contiguous to the hinged end thereof and having an operative connection

with the said hinge member, said lever extending diagonally across the gate forming a strengthening-bar therefor, and means for locking the free end of the lever to the gate-post, substantially as described. 60

2. The combination with a swinging gate, of a hinge arranged at the lower corner of the gate, one member of said hinge being slidably mounted upon the gate, a lever pivoted to the 65 lower corner of the gate and having one end operatively connected to the slidable hinge member, said lever extending diagonally across the gate forming a bar, and means for locking the free end of said lever to the gate-post, substantially as described. 70

3. The combination with a swinging gate, of a hinge arranged at the lower corner thereof and having one of its members slidably mounted upon the gate, a lever pivoted to the lower 75 corner of the gate and operatively connected to the slidable hinge member, said lever extending diagonally across the gate and projecting beyond the free end thereof, and a pair of reversely-arranged keepers, one of 80 which is adapted to receive the lower free end of the gate, the other adapted to engage the free end of the lever, substantially as described.

4. The combination with a swinging gate, 85 of a hinge having one of its members slidably mounted, and a spring engaging the slidable member and exerting a pressure against the weight of the gate, substantially as described.

5. The combination with a swinging gate, 90 of a hinge having one of its members slidably mounted upon the gate, a spring mounted upon the gate and engaging the slidable hinge member, and a lever pivoted to the gate and connected to the slidable hinge member, 95 whereby when said lever is operated the gate is raised or lowered, substantially as described.

6. The combination with a swinging gate, of a hinge having one of its members slidably 100 mounted upon the gate, and a spring engaging the slidable hinge member, a portion of said spring also forming a retaining means for the slidable hinge member, substantially as described.

In testimony that I claim the foregoing as my own I have hereto affixed my signature in the presence of two witnesses.

WILLIAM N. SIMPKINS.
